CIGAR OR CIGARETTE CASE COMBINED
WITH A POCKET LIGHTER

Jules Mellana, Sainte-Croix, Switzerland, assignor to the firm Hermann Thorens Societe Anonyme, Sainte-Croix, Switzerland, a firm of Switzerland

Application January 16, 1939, Serial No. 251,268
In Switzerland January 27, 1938

9 Claims. (Cl. 206—41.4)

This invention relates to cigar or cigarette cases combined with a pocket lighter and more particularly to cases provided with an operating organ for opening the case as well as for actuating the lighter.

The object of the invention is the provision of a case of the above type, comprising an operating organ which can be actuated from outside the case and which can be moved in two different directions, in a first for effecting the opening of the case, and in a second for effecting the working of the lighter.

It is another object of the invention to provide locking means on said operating organ for preventing an accidental actuating of the lighter in the pocket, for instance.

A further object of the invention is the provision of a pocket lighter which is detachably mounted on the case so as to be disconnected from the operating organ and from the case.

The accompanying drawings represent two preferred embodiments of the invention.

Figures 1 to 5 concern the first embodiment, Figure 1 showing it closed and Figure 2 opened. Figures 3 and 4 show details thereof, drawn to a greater scale, and Figure 5 is a section along 5—5 of Figure 3.

Figures 6 to 8 concern the second embodiment. Figures 6 and 7 showing it open in two different positions. Figure 8 refers to a detail.

The embodiment shown in Figures 1 to 5 comprises a shell 1 hinged with the shell 2 in which a lighter 3 is detachably mounted and which presents a recess 4 for the cigarettes to be slipped behind the strip 5.

The bottom of the lighter is provided with a transversal groove 6 of dovetail shaped cross section, which can be engaged on a projection 7 of corresponding shape rigidly carried by the shell 1 of the case. 8 is a lever journalled with its median portion on the body of the lighter. This lighter presents furthermore a wick 9, a cap 10, a friction wheel 11 against which a stone of ferrocium 12 is pressed, and a spring 13 which is constantly tending to lift the cap, which would effect the rotation of the friction wheel 11; in that case this wheel generates by the friction with the stone 12 sparks which fall on the wick 9. In normal position the cap 10 is kept closed due to a heel 14 provided thereon which abuts against a nose 15 of the lever 8 which is submitted to the action of the spring 13 tending to maintain the lever in the position shown in Fig. 3.

16 is an operating organ disposed in an opening 17 of the raised border of the shell 1, and

thereon a latch 19 having the shape of an L is rotatably mounted in 18. This operating organ is kept in the position shown in Fig. 3 by a spring 20 and is connected with the upper end of the lever 8 of the lighter by a bar 21 ending in a hook 22.

In Figures 3 and 5 the lighter and the case, respectively, are closed. In order to open the case, it will be sufficient to press the operating organ 16 inwardly against the spring 20. The lateral nose 23 of this organ (see Fig. 5) will thus be moved downwardly for releasing the two shells from their closing position. For actuating the lighter the latch 19 is moved from its locking position shown in Fig. 3 into unlocking position shown in Fig. 4. In the locking position the big leg of the latch is applied against the upper face of the operating organ 16, while the small leg abuts against an edge at the opening 17 in the raised border of the shell 1, the latch being kept in this locking position by the action of the spring 20 which presses on the lower end of the small leg. In unlocking position the big leg of the latch projects beyond the operating organ while the small leg is now placed at the external side of the wall of the case. If you press with a finger against the left face of the big leg (Fig. 4), the operating organ 16 slides from the left to the right and a traction is thus exerted by the hook 22 upon the upper end of the lever 8, wherethrough the nose 15 of the latter disengages the heel 14 of the cap which opens.

The latch 19 is a substantial part of the operating organ 16 and hingedly mounted on said organ. In consequence, organ 16 and latch 19 are to be pushed down as a whole against the spring 20, and further, in the position of Fig. 4 they are to be slid as a whole from the left to the right when pressing with a finger against the left face of the big leg of the latch. It is to be seen, therefore, that the latch is not in the way for pushing down the organ 16, and moreover, to slide said organ it is not necessary to engage the organ itself as the big leg of the latch 19 which then projects beyond said organ serves as a handle to effect the sliding.

The case, therefore, can always be opened, but the lighter cannot be operated as long as the latch 19 has not been moved against the action of the spring 20 into unlocking position. In this way an accidental actuating of the lighter in the pocket is prevented. On the other hand, with the latch 19 once put into unlocking position, the lighter can be actuated whilst the case is open or closed. If it is open, the lighter can besides be operated

by pressing with a finger on the lower end of the lever 6.

The embodiment shown in Figures 6 to 8 comprises a lighter 27 and an operating organ 16 similar to those above described. This case presents a band 24 on each of the rims of which is hinged a shell 25, respectively 26. The lighter 27 disposed between the shells is fixed in a detachable manner with the bottom of its body to the band 24; for that purpose this bottom is provided with a longitudinal dovetailed groove 28, to be engaged by a corresponding projection 29 slipped therein and which is fixed to the band and longitudinally slotted in 30 in a way to create a certain elasticity. The case can be put up like a stand as shown in Fig. 7, the lighter being in that case disposed upright on the band, ready for use independently from the organ 16.

What I claim is:

- 20 1. In combination with a case for cigarettes or the like of a pocket lighter, lighter actuating means carried by said lighter, and an operating organ movably mounted on said case, being in mechanical connection with said lighter actuating means, and being operable from outside the case for movements in two different directions, in one for effecting the opening of the case and in another for actuating the lighter, and control means mounted on said operating organ and movable into two positions, one which permits the opening of the case while preventing the actuation of the lighter and the second in which the operation of the lighter is effected separately.
- 25 2. In combination with a case for cigarettes or the like of a pocket lighter, lighter actuating means carried by said lighter, an operating organ movably mounted on said case, being in mechanical connection with said lighter actuating means, and being operable from outside the case for movements in two different directions, in one for effecting the opening of the case and in another for actuating the lighter, and a latch rotatably mounted on said operating organ so as to take two stopping positions, a locking one wherein it abuts against a relatively stationary part of the case for permitting said first mentioned movement, while preventing the second movement, and an unlocking position for permitting the second movement only.
- 30 3. In combination with a case for cigarettes or the like of a pocket lighter, lighter actuating means carried by said lighter, an operating organ movably mounted on said case and being in mechanical connection with said lighter actuating means, a spring means resiliently applied against said operating organ, said organ being pushable inwardly from outside the case against the action of said spring means for effecting the opening of the case, and a latch rotatably mounted on said operating organ so as to take two stopping positions, a locking one wherein it abuts against a relatively stationary part of the case for permitting only said pushing movement with the operating organ, and an unlocking position for permitting only a sliding movement of the operating organ along a relatively stationary part of the case, in a direction different from that one of the pushing movement, for actuating the lighter.
- 35 4. In combination with a case for cigarettes or the like of a pocket lighter, lighter actuating means carried by said lighter, an operating organ movably mounted in an opening of the wall of the case, being in mechanical connection with said lighter actuating means, and being operable from outside the case for movements in two different

directions, in one for effecting the opening of the case and in another for actuating the lighter, and a latch formed of two legs in the shape of an L, rotatably mounted on said operating organ so as to take two stopping positions, a locking one wherein one of said legs abuts against an edge of the wall of the case at said opening, while the other leg is applied to the operating organ, for permitting only said first mentioned movement, and an unlocking position wherein the first of said legs is placed at the external side of the wall of the case, while the second is projecting beyond said operating organ, for permitting only the second mentioned movement of said organ.

5 5. In combination with a case for cigarettes or the like of a pocket lighter, lighter actuating means carried by said lighter, an operating organ movably mounted in an opening of the wall of the case and being in mechanical connection with said lighter actuating means, a spring means resiliently applied against said operating organ, said organ being pushable inwardly from outside the case against the action of said spring means for effecting the opening of the case, and a latch formed of two legs in the shape of an L, rotatably mounted on said organ so as to take two stopping positions, a locking one wherein one of said two legs abuts against an edge of the wall of the case at said opening and is engaged by said spring means for maintaining it in this position, while the other leg is applied to the operating organ, and an unlocking position wherein the first of said legs is placed at the external side of the wall of the case, while the second is projecting beyond said operating organ, for permitting only a sliding movement of the operating organ along a part of the wall of the case for actuating the lighter.

6. In combination with a case for cigarettes or the like of a pocket lighter, a spring controlled lighter actuating lever journaled in its median portion on the body of the lighter, and an operating organ movably mounted on said case, being in mechanical connection with one end of said lever and being operable from outside the case for movements in two different directions, in one for effecting the opening of the case and in another for moving said lever against the action of said controlling spring to actuate the lighter, said lever being at its other end also directly operable by hand.

50 7. In combination with a case for cigarettes or the like constituted by a band and two shells each hingedly mounted on a rim of said band, of a pocket lighter disposed inside the case between said shells and mounted in a detachable manner with the bottom of its body on said band, lighter actuating means carried by said lighter, and an operating organ movably mounted on said case, being in mechanical connection with said lighter actuating means, and being operable from outside the case for movements in two directions, in one for effecting the opening of the case and in another for actuating the lighter.

55 8. In combination with a case for cigarettes or the like constituted by a band and two shells each hingedly mounted on a rim of said band, of a pocket lighter disposed inside the case between the two shells, a longitudinal projection rigidly carried by said band, respectively by the bottom of the body of said lighter, a longitudinal groove provided in the bottom of the lighter body, respectively in said band, for engaging said projection slipped therein, lighter actuating means carried by said lighter, and an operating organ movably mounted on said case, being in mechanical connection with said

50

lighter actuating means, and being operable from outside the case for movements in two directions, in one for effecting the opening of the case and in another for actuating the lighter.

- 5 9. In combination with the case for cigarettes or the like constituted by a band and two shells each hingedly mounted on a rim of said band, of a pocket lighter disposed inside the case between the two shells, a longitudinal projection rigidly carried by said band, respectively by the bottom of the body of said lighter, said projection being slotted in a way to be elastic, a longitudinal
- 10

groove provided in the bottom of the lighter body, respectively in said band, for engaging said projection slipped therein, lighter actuating means carried by said lighter, and an operating organ movably mounted on said case, being in mechanical connection with said lighter actuating means, and being operable from outside the case for movements in two directions, in one for effecting the opening of the case and in another for actuating the lighter.
